UNITED STATES PATENT OFFICE.

ARTHUR EFRAIM SILANDER, OF BERLIN, GERMANY.

BRUSH-MAKING.

1,137,915.

Specification of Letters Patent.

Patented May 4, 1915.

Application filed February 9, 1914. Serial No. 817,511.

To all whom it may concern:

Be it known that I, ARTHUR EFRAIM SILANDER, a Finnlander, subject of the Czar of Russia, residing at 6 Culmbacherstrasse, Berlin, W. 50, Germany, have invented new and useful Improvements in Brush-Making, of which the following is a specification.

The primary object of this invention has been to devise certain improvements in apparatus for making brushes the invention being designed with a special view of affording advantageous instrumentalities for facilitating the inserting of bristles or hairs into the head of a brush or broom.

15 The apparatus of this invention enables the holes of the head of the brush to be easily and completely filled with the bristles without making necessary the tapping of the bristles into the holes.

20 Further, according to this invention parallel rods are arranged passing transversely through the bristle container, and means are provided for giving to and fro movement to the edges of the rods crossing the 25 longitudinal axis of the container and supporting the bristles, so that the point of support of the bristles is changed so that they fall into the guiding passages either vertically or approximately vertically.

30 Yet further, the invention comprises the arrangement of hoods above these rods in order to provide for adjustment of the interspace between the rods according to the length of the bristles.

35 Again, yet another feature of the invention consists of a carriage, the portion of which receiving the head of the brush and the mold device above referred to, is so adjustable up and down that in each position 40 the head of the brush and the mold device both lie parallel to the bristle container.

Finally, the invention comprises a stripping device provided in front of the bristle container which strips off the superfluous 45 bristles when the full brush head and mold device are drawn out of the machine.

Some embodiments of the present invention are illustrated in the accompanying drawings, in which—

50 Figure 1 is a vertical cross-section, and Fig. 2 a vertical longitudinal section of a machine embodying the invention. Fig. 3 is a fragmentary view of a portion of the bristle container seen toward the top of 55 Fig. 1. Figs. 4 to 7 illustrate modifications

of Fig. 3, while Fig. 8 illustrates diagrammatically the direction of the bristles in the guiding channels.

Referring more particularly to Figs. 1 and 2 of these drawings, the machine is formed with two side walls 1, which are connected together by means of plates 2. In the lower part of the frame formed by these members a driving shaft 3 is mounted. This shaft is driven from an electric motor or the like. 60 Vertical guiding slots 4 are formed in the upper parts of the side walls. These slots serve to guide the slides 5 during their upward and downward movements. The slides 5 have two outwardly projecting pins 6, upon 65 which connecting rods 7 are hinged. These connecting rods are each joined at their other end with an eccentric strap 8. These eccentric straps embrace eccentrics 9 which are keyed on to the ends of the shaft 3 projecting beyond the framing. The two slides 70 5 derive their up and down motion from the rotation of the shaft 3. These two slides have two inwardly projecting ears 10. A rectangular frame 11 is fastened on these 75 ears and so takes part in the upward and downward movement of the two slides. This frame serves as a container for the bristles or hairs. Spiral springs 12 are fastened at one end to the edges of this frame and at 80 the other end engage with pins 13 fixed upon the side walls 1. These springs have the function to draw the frame 11 and with it the slides 5 upward so that a motion is obtained which is as free from shock as possible. 85

The lower part of the frame is made in the form of a funnel or hopper, as can be seen in Fig. 1, and is fitted with a number of longitudinal walls 14, which are spaced 90 wider at the top than below, so that small funnels are formed by these intermediate walls and are further divided by a cross wall 15.

The head 22 of the brush or broom, and 100 the corresponding guiding or mold device, are arranged in known manner below the container. A cross bar 16 is arranged on the inside of each side wall 1 below the bristle container for this purpose, and serves as a 105 running surface for the carriage 18 running upon rollers 17. Bolts 20 are screwed into suitable internally-threaded holes 19 on the sides of the carriage. These bolts are rotatably arranged in a frame or board 21 110

which is designed to receive the head 22 of the brush and the mold device. Sprocket wheels 23 are fixed on the bolts 20 and over these wheels an endless chain 24 passes. By 5 pulling this chain either to the right or to the left the sprocket wheels 23, and with them the bolts 20, are correspondingly rotated and by this means are screwed further into the holes 19 in the carriage or are unscrewed from these holes. In this way the 10 position of the frame 21 relatively to the lower edge of the bristle container 11 can be adjusted. Also, by this means sufficient adjustment of the mold device and head of the brush relatively to the bristle container is 15 provided and it is possible to determine the most favorable position for the mold device and head of the brush.

A rod 25 is provided on the front part of 20 the carriage to serve as a handle for drawing the carriage from below the bristle container 11 along the bars 16 serving as rails in order to regulate the working of the machine and to replace the mold and brush head filled with bristles by empty ones. A 25 comb 26 is provided on the front part of the machine and is so arranged that when the carriage is drawn out the bristles lying across the top of the brush head are cleared off. A collecting receptacle 27 for catching the bristles which do not pass into the head of the brush is provided below the carriage.

Immediately above the funnels or hoppers in the bristle container rods 28 of oval 30 cross section are rotatably mounted longitudinally. The 1st, 3rd, 5th, 7th and so on rods are connected together by means of a hinged rod 29 (see Figs. 1 and 3). This rod 35 projects from the frame 11 to the right 40 of the bristle container and carries a roller 30 which is pressed by means of a spring bearing against the wall of the frame against a curved cam track 33 fixed on the frame of the machine by means of flanges 45 31. The 2nd, 4th, 6th, 8th and so on rods 28 are connected together through a further hinged rod 34, which similarly projects from the frame 11 of the bristle container to the right and similarly carries a roller 35 which 50 is pressed by means of a spring 36 against the cam track 33.

During the upward movement of the bristle container 11 rods 29 and 34 are 55 pressed inward by the cam track 33 so that the rods 28 take up the position shown in Fig. 3, and upon the downward movement of the bristle container again return to the position shown in Fig. 1. By this means, as is evident without further explanation, the 60 points of support of the bristles are changed and the bristles are caused to fall down into the funnels in a greater number. This is specially facilitated owing to the consequent rotation of the rods 28 toward one another. 65 It is possible to work with bristles in this

device which are longer than the free width of the funnel passages, that is to say, in consequence narrower funnels can be employed, and this makes it possible to guide the bristles better. This is diagrammatically 70 shown in Fig. 12, in which it may be seen in the left hand illustration that with broad channels the position of the bristles deviates considerably from the vertical and the bristles when brought up to the head of the brush rest crosswise and stop further work. On the contrary, when narrower channels are used, as is shown in the right hand diagram, the bristles take up a position deviating very little from the vertical. 75 80

As is shown in Figs. 4 and 5 vertical strips of sheet metal 37 may be arranged above the funnels, alternate strips being hinged at the lower extremity and be rocked backward and forward by means of rod 38 (see Fig. 85 5). By this means also a change in the point of support of the bristles is brought about and the same are caused to fall more quickly into the funnel. Instead of rocking the strips of metal these can be pushed backward and forward in a simple manner as is 90 illustrated in Fig. 6.

In order to enable short bristles to be used hoods 39 are inserted above the rods 28 (see Fig. 5). These hoods are of a certain 95 breadth at the top in order to cause the points of support of the bristles to approach one another more nearly. The rods 28 and 37 can also be mounted in the frame 100 of the machine and can be driven in any desired manner so that they do not take part in the movement of the bristle container.

What I claim is:—

1. In a machine for the manufacture of 105 brushes or brooms, the combination of a container for the bristles or hairs, passages leading from said container, means for agitating said container, means for supporting a brush head below the outlet orifices of 110 said passages with its holes in register therewith, a series of parallel horizontal rods mounted in said container and means to operate the rods for effecting transverse movement of the edges of said rods supporting the bristles. 115

2. In a machine for the manufacture of 120 brushes or brooms, the combination of a container for the bristles or hairs, funnel-shaped passages leading from said container, means for agitating said container, 125 means for supporting a brush head below the outlet orifices of said passages with its holes in register therewith, a series of parallel rods pivotally mounted in said container, a pair of hinged rods each connecting alternate members of said parallel rods and means for actuating said hinged rods for rocking the alternate members of said parallel rods in opposite directions. 130

3. In a machine for the manufacture of 130

brushes or brooms, the combination of a container for the bristles or hairs, funnel-shaped passages leading from said container, means for agitating said container, 5 means for supporting a brush head below the outlet orifices of said passages with its holes in register therewith, a series of parallel rods pivotally mounted in said container, a pair of hinged rods each connecting alternate members of said parallel rods and 10 means operated by the agitation of said container for rocking the alternate members of said parallel rods in opposite directions.

4. In a machine for the manufacture of 15 brushes or brooms, the combination of a container for the bristles or hairs, passages leading from said container, means for agitating said container, means for supporting a brush head below the outlet orifices of 20 said passages with its holes in register therewith, a series of parallel rods mounted in said container, means for moving the said rods, and a plurality of hoods each disposed above one of said rods to decrease the free 25 space between adjacent rods.

5. In a machine for the manufacture of 30 brushes or brooms, the combination of a container for the bristles or hairs, funnel-shaped passages leading from said container, means for agitating said container, a carriage arranged below said passages; a table surmounting said carriage, and below 35 said passages to receive the brush heads and lifting gear operative upon said table to raise it relatively to said carriage parallel to the original position thereof.

6. In a machine for the manufacture of 40 brushes or brooms, the combination of a container for the bristles or hairs, funnel-shaped passages leading from said container, means for agitating said container, a carriage arranged below said passages; a table surmounting said carriage and below 45 said passages to receive the brush heads, lifting gear operative upon said table to raise it relatively to said carriage parallel to the original position thereof, running rails for said carriage and a handle for withdrawing said carriage from the machine upon said 50 rails.

7. In a machine for the manufacture of 55 brushes or brooms, the combination of a container for the bristles or hairs, funnel-shaped passages leading from said container, means for agitating said container, a carriage arranged below said passages; a table surmounting said carriage and below 60 said passages to receive the brush heads and lifting gear operative upon said table to raise it relatively to said carriage parallel to the original position thereof; running rails for said carriage, a handle for withdrawing said carriage from the machine upon said rails, and a comb disposed 65 upon the frame of the machine at the front

part thereof in position to remove the loose bristles upon the withdrawal of said carriage.

8. In a brush making machine, the combination of a container to receive bristles or 70 hairs, passages leading from said container to convey the hairs to a brush head, a plurality of spaced parallel rods mounted in said container and adapted at their upper edges to support the bristles in the container, and means to operate the rods to move the said upper bristle supporting edges to and fro transverse to the direction of their length. 75

9. In a brush making machine, the combination of a container for bristles or hairs, 80 passages leading from the bottom of said container through which the bristles may be supplied to a brush head, a plurality of spaced horizontal rods arranged in said container, each of said rods being vertically elongated in cross section and being adapted at its upper edge to support the bristles, means for agitating the container, and means for rocking said rods to move their bristle 85 supporting edges in a direction transverse to their length for the purpose described.

10. In a brush making machine, the combination of a container for bristles or hairs, 90 passages leading from the bottom of said container through which the bristles may be supplied to a brush head, a plurality of spaced horizontal rods arranged in said container, each of said rods being vertically elongated in cross section and being adapted 95 at its upper edge to support the bristles, means for agitating the container, and means for moving said rods back and forth transversely of their longitudinal axis and cross-wise of the container for the purpose described. 100

11. In a brush making machine, the combination of a container to receive bristles or hairs, 110 passages leading from said container to convey the hairs to a brush head, a plurality of spaced parallel rods mounted in said container and adapted at their upper edges to support the bristles in the container, means for operating the rods to move said upper bristle supporting-edges of the rods 115 to and fro transverse to their longitudinal axes, and hoods inserted above said rods whereby to vary the operative space intermediate the same.

12. In a brush making machine, the combination of a container adapted to receive bristles, 120 passages leading from said container through which the bristles may be supplied to a brush head, a carriage arranged below said passages, a table surmounting said carriage, means for withdrawing the carriage from the machine, and means arranged for striking off the superfluous bristles of a brush head on the carriage as the latter is withdrawn. 125 130

13. In a brush making machine, the combination of a container adapted to receive bristles, passages leading from said container through which the bristles may be supplied to a brush head, a carriage arranged below said passages, a table surrounding said carriage, means for withdrawing the carriage from the machine, and a comb supported adjacent to the carriage
10 arranged to strike off superfluous bristles

from a brush head withdrawn with the carriage.

In testimony whereof I have signed my name to the specification in the presence of two subscribing witnesses.

ARTHUR EFRAIM SILANDER.
